PORTABLE BARBECUE UNIT

Rulon J. McQuarrie, Los Angeles, Calif.

Application April 27, 1954, Serial No. 30,220

Term of patent 14 years

(Cl. D81—10)

FIG. 1.

FIG. 2.

To all whom it may concern:

Be it known, that I, Rulon J. McQuarrie, a citizen of the United States, residing at 212 South Carmelina Avenue, Los Angeles, State of California, have invented a new, original, and ornamental Design for a Portable Barbecue Unit, of which the following is a specification, reference being had to the accompanying drawing, forming a part hereof:

I claim:
The ornamental design for a portable barbecue unit, substantially as shown.
